CLAIM

The ornamental design for an injection device, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an injection device, showing a first embodiment of our new design;
FIG. 2 is a front elevation view thereof;
FIG. 3 is a rear elevation view thereof;
FIG. 4 is a side elevation view thereof;
FIG. 5 is an opposite side elevation view thereof;
FIG. 6 is a top plan view thereof;
FIG. 7 is a bottom plan view thereof;
FIG. 8 is a perspective view of an injection device, showing a second embodiment of our new design;
FIG. 9 is a front elevation view thereof;
FIG. 10 is a rear elevation view thereof;
FIG. 11 is a side elevation view thereof;
FIG. 12 is an opposite side elevation view thereof;
FIG. 13 is a top plan view thereof; and
FIG. 14 is a bottom plan view thereof;
FIG. 15 is a perspective view of an injection device, showing a third embodiment of our new design;
FIG. 16 is a front elevation view thereof;
FIG. 17 is a rear elevation view thereof;
FIG. 18 is a side elevation view thereof;
FIG. 19 is an opposite side elevation view thereof;
FIG. 20 is a top plan view thereof; and,
FIG. 21 is a bottom plan view thereof.
